UNITED STATES PATENT OFFICE.

CHARLES J. VAN DEPOELE, OF CHICAGO, ILLINOIS.

ELECTRO-MAGNETIC RECIPROCATING ENGINE.

SPECIFICATION forming part of Letters Patent No. 337,897, dated March 16, 1886.

Application filed June 24, 1885. Serial No. 169,645. (No model.)

To all whom it may concern:

Be it known that I, CHARLES J. VAN DEPOELE, a citizen of the United States of America, residing at Chicago, in the county of Cook and State of Illinois, have invented certain new and useful Improvements in Electro-Magnetic Reciprocating Engines, of which the following is a specification, reference being had therein to the accompanying drawings.

10 My invention relates to certain new and useful improvements in that class of electric engines similar to that shown in my application having the Serial No. 155,246, filed February 7, 1885, and is more particularly adapted for mining or other similar purposes; and the invention consists in the peculiar combinations and the construction and arrangement of parts hereinafter more particularly described, and then pointed out in the claims.

20 In the accompanying drawings, Figure 1 shows a side elevation of an engine constructed according to my improvement. Fig. 2 shows a plan of the same. Fig. 3 is a horizontal longitudinal section without the wheels shown in the previous figures. Fig. 4 is a plan view of the same, showing a lamp and its connections and with a different form of connection between the motor and brush-holders. Figs. 5, 6, 7, and 8 are enlarged details, which will be more fully described hereinafter. Fig. 9 is an end view, partly broken away. Fig. 10 is a partly-sectional side view. Fig. 11 shows a detail of a commutator provided with a rolling brush. Fig. 12 shows an elevation of the brush indicated in Fig. 11, detached.

In the different figures similar letters indicate similar parts.

A is a diamagnetic rod, carrying at one end 40 the tool or cutter, and having its other end solidly affixed to the iron core or plunger B, which is driven to and fro under the influence of the current in the surrounding solenoid formed of a number of flat copper sections or 45 coils, F F, the inner end of one coil being connected to the outer end of the next throughout the entire series, as usual.

C is a brass tube or cylinder, carrying the sections of the solenoid and slotted longitudinally the whole length occupied by said sections, and carrying at one end a bearing, C', for the rod A.

D and D' are two soft-iron heads, mounted upon the cylinder C and holding the sections F F of the solenoid in place. 55

E is a tube or cylinder of soft iron, fitted upon the heads D and D', which tube is preferably cut open longitudinally, so as to give passage to the wires from the sectional solenoid to the commutator placed above it. 60

The sections of the solenoid F F are provided with the terminals f, electrically connected to the flat plates 1 and 2, (see Fig. 6,) which are in turn placed against the sections L of the commutator. 65

G is a plate or top, of wood or other insulating material, upon which the commutator and accompanying parts are mounted, and thus insulated from the frame of the machine.

H and H' are guides for the commutator-brushes, on which run the slides I I' I'' I''', attached to the brush-holders J J', which carry contact-brushes made of fine copper-leaf strips set against each other and soldered at their upper edges, or otherwise secured together. 70

At K and K' are shown two strips of insulating material—such as vulcanized fiber or other suitable substance—holding the brush-holders and brushes apart and insulating the same from one another. 80

The construction and arrangement of these brush-holders are more clearly shown in the enlarged view, Fig. 8, which represents a horizontal section of the same. An examination of this will show that the holder J is attached on one side by a single screw to the insulating-strip K, and that the slide I' is only connected with it by the insulating material, and is not, therefore, in electrical connection with it. The slide I on the other side, however, is electrically connected with the brush-holder by means of two screws, which pass through the insulating material into ears j j, formed on the brush-holder J. The slide I'' of the other brush-holder, J', is arranged reversely—that is to say, the opposite guide, I'', is electrically connected with the brush-holder while I''' is not. 85

To keep the brushes in contact with the commutator, I employ a spring, u, which can 90 be adjusted by a set-screw, v, which passes through the top of the brush-holder. The guide H is electrically connected with the positive post P o, while the other guide, H',

is connected to a conductor which is also connected to a motor, M, and a lamp, U, herein-after referred to, and from both of which the current returns to the negative post N e.

5 The commutator is formed of sections L, disposed as shown in detail in Fig. 5, where L L L L are the copper commutator-sections, against each of which a contact-plate, as 1 or 2, (see Fig. 6,) is placed, each contact-plate 10 touching one copper section, and is therefore in electrical contact with the same and with one of the sections of the solenoid. Between each following pair is placed a plate of insulating material, thus keeping the consecutive 15 sections insulated from each other, and when all the plates and contacts are in place they are kept together by top plates, e and e', insulated from commutator-sections by means of hard rubber or other similar material, and 20 screwed tight together on the ends by means of screws s, (see Fig. 11,) bearing on the end plates, so that in case of repairs or replacing of copper sections all there is to do is to take out the flat sections and their insulations and 25 to replace the same by new ones. The contact-plates need not be disturbed, and will last indefinitely, always making a good connection between the sections of the solenoid and the commutator-sections.

30 M is an independent minor electric rotary motor of any approved form, having a crank, P, which, through the pitman N and pin O, moves the brushes to and fro over the rectangular commutator, thus shifting the current 35 from end to end in the sectional solenoid, and producing the to-and-fro motion of the iron core B, and with it the rod A, and which will transfer the motion of the core B to any tool or instrument connected with said rod A.

40 This motion of the brushes is shown as accomplished in two ways. In Figs. 1 and 2 the pitman is pivotally connected at one end with the crank-pin p of the motor, while the other end has a long slot in which is a pin, O, connected to the system of brushes, which slot is intended to produce a lost motion between the pitman and the brushes at O, which will allow the current to pass for a considerable 45 length of time at each end of the solenoid, and 50 has the effect of increasing the strength of the blow by allowing more time for magnetizing the heads D D'.

Fig. 4 shows a somewhat different mode of changing the current in the sectional solenoid. 55 In this arrangement the pitman has one end pivotally connected to the brush-holder, and the other end has a hook by which it is loosely connected to crank P. The pitman in this case moves under guide R and between springs r', 60 which tend to keep the pitman in a central position.

At Q is a stop, fixed to the frame of the motor, which holds the pitman in the position shown until the crank-pin p has slipped out 65 of the hook on the end of the pitman, when an adjustable spring, S, connected to the brush-holders will carry the brush-holders and pit-

man rapidly forward. The action of these parts is as follows: When the brushes are in their extreme forward position, or opposite to that shown in Fig. 4, the crank-pin p, as it revolves, will catch the hook of the pitman N and carry it around until the latter strikes the stop Q, which prevents the pitman following the crank-pin P. The motor, however, keeps on turning, and the crank P leaves the pitman behind. At the instant this occurs the spring S pulls the brushes forward over the commutator with great rapidity, producing a correspondingly-accelerated motion of the iron core B, thus obtaining a high velocity and a heavy blow. The crank will then again engage the hook of the pitman and again carry the brushes and pitman to the position shown in Fig. 4, where the pitman is again stopped by the stop Q, and the before-mentioned motions repeated as long as the current is in action. The motor, carrying its crank along, will thus alternately draw back and release the brushes, producing a gentle return motion of the iron core 80 and tool, while the forward stroke will be as fast as possible. This will keep on as long as the current is supplied to the machine.

At U is shown an electric lamp provided with a reflector, V, for illuminating the point 95 of the tool or pick, or the point on which it acts, as is generally necessary in coal-mining.

The circuits in the machine are as follows: From a suitable electrical generator the current enters at post P o, (see Fig. 4,) and by a 100 suitable conductor passes to guide-bar H, to slide I, to brush-holder J and its brush J'', through the sections of the solenoid comprised between the two brushes, to the brush and its holder J', through the slide I'' of the latter and 105 the guide-bar H' to conductor X, where the current divides itself, part passing through the lamp U and part through the motor, and then returning from lamp and motor passes to post N, thus completing the circuit. The 110 total current passing through the lamp and motor will equal the current passing through the coils of the solenoid, and by means of a variable resistance the current in motor and lamp can be varied to suit the requirements 115 of speed and light.

From the above description it will be seen that when the current enters the solenoid at the front and leaves at the center the strongest attraction upon the iron core will be 120 toward the head D, the magnetism in the iron tube E being distributed over the whole of its length and communicated to the heads D and D'; but the point of highest magnetic energy is at the inner side of the head D and 125 the front end of the iron core during the forward stroke; but when the current enters at the center and leaves at the rear the reverse takes place, and the back-stroke is the result. The magnetic intensity is greatly increased 130 with the iron tube or envelope, and at the same time it makes a perfect protection for the coils of the solenoid, so that the machine can be roughly handled without fear of injury.

Another advantage is, that the dampness or contact with water is avoided, which such machines are liable to encounter.

In former engines of this type I used a commutator of cylindrical or circular shape, as in my application before referred to; but in the present case I prefer to use a commutator of rectangular shape, as explained above. The chief advantages of this form are the ease of construction and repairs, and it also simplifies the working of the brushes, which, as before explained, are moved by means of a rotary electric motor which is so arranged as to give a spasmodic motion to the brushes running over the commutator, thus producing a quick stroke or blow of the iron plunger in the solenoid. If the pitman were connected directly and solidly to the crank and to the brush-holders, the result would be that the plunger would not be able to travel faster than the motor, and thus, although a reciprocating motion would be produced by the iron core, it would not be a blow such as the machine is intended to give and is requisite for the purpose of mining or other similar work. The device shown in Figs. 1 and 2 I have found in practice to work well, the lost motion between the pitman N and the pin O allowing the motor to obtain a higher velocity just before the pitman strikes the pin O. At the end of the stroke the speed has sensibly decreased; but at the extreme end of the stroke the motor has a chance to get another start and again increases its speed, and so on as long as the motor runs, thus giving a spasmodic motion to the brushes over the commutator and changing with great rapidity the current in the solenoid, which on being shifted gives a quick impulse to the iron core and the tool it carries, and strikes a heavy blow at the object against which it is directed.

The above mode is especially adapted for quick-running machines; but for heavy and slower running apparatus the mode shown in Fig. 4 is preferable, for, no matter how slow the motor runs or how slow the back or return stroke is made, the forward stroke will always be made with great velocity, and consequently with great power, because when the end of the back-stroke has been reached and the pitman is disengaged from the crank-pin P the spring S suddenly pulls the brushes and pitman forward, reproducing a similar sudden forward stroke of the iron core or plunger.

Instead of connecting the motor directly to the crank, a smaller motor can be used by gearing the same back to a larger gear-wheel, which in turn may carry the crank-pin P.

In Figs. 1 to 10 a frictional brush is shown, composed of a number of very thin copper leaves, so disposed as to run edgewise over the commutator-sections, which is held in position by means of a brush-holder provided with a spring so arranged as to bear with more or less force upon the brush, thus preventing the breakage of the circuit between the brush and commutator.

Instead of a frictional brush, a rolling brush (see Figs. 11 and 12) can be used having less wear upon the commutator-sections. This rolling brush is made of fine copper leaves r, stamped out in proper shape and mounted upon a shaft, t, and then clamped fast thereon by means of suitable screw-nuts, u. The disks are separated from each other by means of small copper disks v, so as to leave a space between each adjacent disk of, say, one sixty-fourth inch, which makes the brush more elastic than where all the disks are of the same size. These roller-brushes are mounted upon a suitable frame, and are moved the same as the frictional brushes. They are also held upon the face of the commutator by means of a suitable spring system. (Shown in Fig. 11.)

The electric lamp is placed in front of the machine, as shown in Figs. 1 and 4, and, as before stated, is inclosed in a suitable reflector, which, being made of heavy glass or other material, not only protects the lamp from accidental fracture through the falling of débris or otherwise, but at the same time diverts the light from the operator's eyes and directs the light in the point of the tool, thus enabling the operator to see where and what he is striking.

By the term "continuously-operating motor," used in the claims following, I do not limit myself to a rotary motor, except where specifically claimed, as a reciprocating motor may be substituted for the rotary motor in some of the combinations claimed without departing from the spirit of my invention. Nor do I intend to limit myself to an electro-motor, except where it is specifically stated in the claims, as any other motor may be used as an equivalent.

Many different modes of operating the brushes so as to obtain a quick blow of the iron core and tools outside of the solenoid may be devised, without, however, departing from the spirit of my invention.

What I claim as new is--

1. In an electro-magnetic engine, a solenoid, a core acted on by the opposite ends thereof alternately, a commutator and traveling contacts therefor, and a spring constructed and arranged to carry said contacts to the end of the commutator, energizing the solenoid when the core and the tool carried thereby are delivering their blow, substantially as described.

2. In an electro-magnetic engine, a solenoid, an iron core working therein, and a magnetic cylinder enveloping the solenoid, substantially as described.

3. In an electro-magnetic engine, a solenoid, an iron core working therein, magnetic heads at each end of the solenoid, and a magnetic cylinder enveloping the solenoid, substantially as described.

4. In an electro-magnetic engine, a solenoid, an iron core working therein, and a diamagnetic rod to transfer the core's force and mo-

- tion, a diamagnetic tube inside the solenoid within which the core works, and a magnetic cylinder enveloping said solenoid, substantially as described.
5. In an electro-magnetic engine, a solenoid, an iron core working therein, a diamagnetic rod to transfer the core's force and motion, a diamagnetic slotted tube inside the solenoid within which the core works, and a magnetic cylinder enveloping the solenoid, substantially as described.
6. In an electro-magnetic engine, a sectional solenoid and commutator, an iron core working in the solenoid, and a magnetic cylinder surrounding the solenoid provided with an opening through the center for the connections between the solenoid and its commutator, substantially as described.
7. In an electro-magnetic engine, a sectional solenoid, a core working therein, a rectangular commutator having its sections in electrical connection with the corresponding coils or sections of the solenoid, and contacts for said commutator, in combination with an independent electromotor constructed and arranged to move said contacts oversaid commutator, substantially as described.
8. The combination, with an electro magnetic reciprocating engine and its current-controller, of a rotary electromotor constructed and arranged to operate said current-controller, substantially as described.
9. In an electro-magnetic engine, a solenoid, a core working therein, and a current-controller, in combination with a rotary electromotor in electrical connection with the solenoid, and operating said current-controller, substantially as described.
10. In an electro magnetic engine, a sectional solenoid, a core working therein, a rectangular commutator having its sections in electrical contact with the successive coils of the sectional solenoid, and a pair of contacts traveling over the commutator, in combination with an independent electrical motor operating said contacts, substantially as described.
11. In an electro-magnetic engine, a solenoid, a core acted on by the opposite ends thereof alternately, a commutator connected to the solenoid, and traveling contacts therefor, in combination with an independent motor constructed and arranged to give the traveling contacts an intermittent motion, substantially as described.
55. 12. In an electro-magnetic engine, a solenoid, a core acted on by the opposite ends thereof alternately, a commutator connected to the solenoid, and traveling contacts therefor, in combination with an independent electromotor constructed and arranged to give the traveling contacts an intermittent motion, substantially as described.
13. In an electro-magnetic engine, a solenoid, a core acted on by the opposite ends thereof alternately, a commutator connected to the solenoid, and traveling contacts therefor, in combination with an independent rotary elec-
- tromotor constructed and arranged to give the traveling contacts an intermittent motion, substantially as described.
14. In an electro-magnetic engine, a solenoid, a core acted on by the opposite ends alternately, and a commutator for the solenoid, in combination with an independent continuously-operating motor, traveling contacts for the commutator, and an intermittently-operating connection between the motor and contacts, whereby the contacts are caused to travel rapidly over the commutator and rest at the end of their forward stroke, substantially as described.
15. In an electro-magnetic engine, a solenoid, a core acted on by the opposite ends alternately, and a commutator for the solenoid, in combination with an independent continuously-operating electromotor, traveling contacts for the commutator, and an intermittently-operating connection between the motor and contacts, whereby the contacts are caused to travel rapidly over the commutator and rest at the end of their forward stroke, substantially as described.
16. In an electro-magnetic engine, a solenoid, a core acted on by the opposite ends alternately, and a commutator for the solenoid, in combination with an independent continuously-operating rotary electromotor, traveling contacts for the commutator, and an intermittently-operating connection between the motor and contacts, whereby the contacts are caused to travel rapidly over the commutator and rest at the end of their forward stroke, substantially as described.
17. In an electro-magnetic engine, a solenoid, its traveling core, a commutator, and traveling contacts, in combination with a motor having a crank and a pitman forming a loose connection between the crank and traveling contacts, substantially as described.
18. In an electro-magnetic engine, a solenoid, its traveling core, a commutator, and traveling contacts, in combination with an electric motor having a crank and a pitman forming a loose connection between the crank and traveling contacts, substantially as described.
19. In an electro-magnetic engine, a solenoid, its traveling core, a commutator, and traveling contacts, in combination with a motor provided with a crank having one end positively connected with the traveling contacts and its other end loosely connected with the crank of the motor, and mechanism, substantially as described, for disconnecting the crank and pitman, as set forth.
20. In an electro-magnetic engine, a solenoid, its traveling core, a commutator, and traveling contacts, in combination with a rotary electromotor provided with a crank having one end positively connected with the traveling contacts and its other end loosely connected with the crank of the motor, and mechanism, substantially as described, for disconnecting the crank and pitman, as set forth.
21. In an electro-magnetic engine, a solenoid,

oid, its traveling core, a commutator, and traveling contacts, in combination with a motor having a crank, a pitman having one end positively connected to the traveling contacts and 5 provided with a hook at the other, a stop to disconnect the hook and crank, and a spring to carry the traveling contacts in the opposite direction they were moved by the crank, substantially as described.

22. In an electro-magnetic engine, a solenoid, its traveling core, a commutator, and traveling contacts, in combination with a rotary electromotor having a crank, a pitman having one end positively connected to the 15 traveling contacts and provided with a hook at the other, a stop to disconnect the hook and crank, and a spring to carry the traveling con-

tacts in the opposite directions they were moved by the crank, substantially as described.

23. In an electro-magnetic engine, a sectional solenoid having a rectangular commutator composed of permanent contact-plates in electrical connection with the sections of the solenoid, and detachable wearing-plates, substantially as set forth, and for the purpose 20 25 specified.

In testimony whereof I affix my signature, in presence of two witnesses, this 11th day of June, 1885.

CHARLES J. VAN DEPOELE.
